FIG. 7.

FIG. 6.

FIG. 8.

UNITED STATES PATENT OFFICE.

LUTHER SMITH, OF NORRISTOWN, PENNSYLVANIA, ASSIGNOR OF ONE-TENTH PER CENT TO WILLIAM GREEN, TWO-TENTHS PER CENT TO HAMPTON STEWART, TWO-TENTHS PER CENT TO WILSON SCOTT, TWO-TENTHS PER CENT TO MONTGOMERY WILSON, AND TWO-TENTHS PER CENT TO SMITH DARBY, ALL OF NORRISTOWN, PENNSYLVANIA.

RAILWAY-RAIL JOINT.

Application filed November 6, 1925. Serial No. 67,440.

To all whom it may concern:

Be it known that I, LUTHER SMITH, a citizen of the United States, residing at Norristown, in the county of Montgomery and State of Pennsylvania, have invented certain new and useful Improvements in Railway-Rail Joints, of which the following is a specification.

This invention relates to certain new and useful improvements in railway rail joints, and in railway chairs used in connection therewith.

One of the objects of my invention is to provide means for so supporting the confronting ends of the rails at their point of junction as to form a smooth continuous track and overcome the tendency to sag at that point, and thus to obviate the necessity of constant repairs.

Another object of my invention is to so connect together the rails at the point of juncture as to avoid the possibility of their working loose at that point.

A further object of my invention is to so construct the rails and the chair in which they are placed as to strongly and durably support their ends and thus give them long life at the point where they are now most inclined to wear.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

In order to make my invention more clearly understood, I have shown in the accompanying drawings means for carrying the same into practical effect without limiting the improvements in their useful applications to the particular constructions, which for the purpose of explanation, have been made the subject of illustration.

In the drawings:

Figure 1 is a perspective view of my improved rail joint as it appears in use; 50

Fig. 2 is a central horizontal sectional view of Fig. 1;

Fig. 3 is a section taken on the line 3—3 of Fig. 1;

Fig. 4 is a section taken on the line 4—4 55 of Fig. 1;

Fig. 5 is a section taken on the line 5—5 of Fig. 1;

Fig. 6 is a perspective view showing the configuration of one end of a rail; 60

Fig. 7 is a perspective view of the confronting end of the opposite rail;

Fig. 8 is a perspective view of the joint or chair in which the rail ends fit and are locked; and 65

Fig. 9 is a vertical, central longitudinal view of the rail joint as it appears when assembled.

Referring more particularly to Figs. 6 and 7, the numeral 1 refers to one end of a 70 railway rail and the numeral 2 refers to the end of another rail made in accordance with my design, and the numerals 3 and 4 refer to the confronting ends of said rails which are adapted to be locked together, as will 75 more fully hereinafter appear. Each end of each rail is made precisely alike so as to permit of the use of either end while they are being laid, and as a description of one of them only is necessary, the other will 80 not be particularly referred to at this time.

The web of the rail end, as seen in Figures 6 and 7, is provided with a kerf 5 extending across the end, and just beyond this kerf is a square opening 6 extending partially 85 through, and the lower edge of the web, for a distance corresponding to the length of this opening, is beveled, as at 7. Beyond this point and towards the farther end of the web and on the under side thereof, the 90 body is provided with a depending retaining or locking lug 9 adapted to fit in a hole 10 in the bottom of the rail chair 11 (see Fig. 9) and a slight distance beyond this point is a boss 12 extending out from the 95 rail web and lower part of the crown 13 of

the rail and integral therewith. This boss 12 on the end facing the confronting rail is provided with a socket 13' which forms a seat for the reception of a bolt to be presently described.

Referring to the perspective views shown in Figures 1 and 8, we see a railroad chair comprising a base 11 and a body 14 integral therewith, the former provided with spike 10 holes 17 for the reception of the spikes whereby the chair is fastened to the railroad ties. The body has a horizontal slot 18 (see Fig. 8) for the reception of that part of the web of the rail heretofore described 15 and on the further side of the chair there is a strengthening and supporting rib 19 extending the length of the rail chair and upon which the car wheel is largely supported as it passes over the juncture of the rails, the 20 rib being made to extend up even with the crown 13 of the rail.

The central portion of the body of the chair is not so thick as the end portions, the part numbered '19' being provided with 25 apertures at 20 and 21 (see Fig. 2) for the reception of side locking pins 24 and 25. The outer ends of these pins are each provided with a spike head 26, the other end of said pins being squared off as at 27 (except on its upper side 32) to form a locking 30 or bolt head, and the body of the pin is surrounded by a spiral spring 28. The purpose of the spring is to push the pin inwardly and drive its square head into the 35 hole or orifice 6 shown in Fig. 6, which forms its seat.

In order to unlock this pin, the trackman uses his pinch bar to force the head outwardly towards himself when the same is 40 withdrawn from its seat.

Referring again to the side locking pins 24 and 25, should it become necessary to remove the rails, it is to be noted that in replacing the rails, the downward pressure 45 of the beveled edge 7 comes upon the rounded upper edge 32 of the lock head of the pin and by reason of the contour of the lock head forces the pin outwardly against the pressure of the spiral spring, the latter 50 receding until the orifice 6 comes opposite and slightly below the lower edge of the lock head, when the spiral spring drives the locking pin back into its seat in the orifice 6 in the web.

55 The numeral 30 represents a central lock bar. Its body is flat and extends through the side of the chair at its center, and through each of the kerfs 5 in the ends of the respective rails. As seen in Fig. 2, after 60 it passes through the web, it terminates in an elongated pin 31 having a hole 32' bored therethrough near its end into which fits a cotter or other pin 33, the same standing in a recess 33' in the far side of the chair. 65 This central lock bar passes thus through

both sides of the chair and through the web of each rail and effectually locks both ends of the rails and the chair together.

The side locking pins are located on the side of the chair facing the road bed between 70 the rails and extend through that side of the chair and partially into the web of the rail, but no provision is made for like pins on the other side of the chair.

The chair at each of its respective ends is provided with an integral block 35, as is more particularly seen in Figure 8, said blocks being provided with dovetail passages 36 extending longitudinally therein, in which slide the beveled edges of a bolt 37, 75 the bolt being provided at one end with a head 38, beyond which is a spiral spring 39, the purpose of which latter is to push the bolt head into the seat 13' in the boss 12 shown in Figure 7, thus effectually locking 80 the ends of the chair to the rail.

From the above it will be seen that the chair is strongly spiked to the rail ties; that the web of each rail at its end fits therein, its bottom is locked to the bottom of the chair by the locking lug 9; the end of each rail is secured by the central locking pin 30 by the side locking pins 24 and 25, and the chair itself is secured to the rails by the end locking bolts 37.

In laying the track, the chair is put in its proper position and the confronting ends of the opposite rails laid therein, the bolts 37 having first been pushed towards one another by means of the bolt heads 38. The depending lugs 9 on the rails fall into their proper recesses in the base of the chair and as soon as this occurs, the bolts 37 are automatically pushed home in the sockets 13' by the springs 39 and the chair is then spiked to the tie.

The central locking bar 30 is then pushed in through one side of the chair, the kerfs in the ends of the rails and through the other side of the chair and the cotter pin 33 inserted near the extreme end of the pin. In order to secure further rigidity, the locking pins 24 and 25 are provided, which as seen in Fig. 1 extend partially through the web and add their strength to hold the rails down in place and to counteract the tendency of the rails to rise immediately after the passage of the wheels of the cars over the joint.

When it is desired to remove the rails, the central locking bar 30 is removed, the trackman then uses his pinch bar to force the side pins 24 and 25 outwardly from their seats, the bolts 37 are withdrawn and the rails are lifted from their positions in the 125 chair.

While I have shown and described the preferred embodiment of my invention, I wish it to be understood that I do not confine myself to the precise details of construction 130

herein set forth, by way of illustration, as it is apparent that many changes and variations may be made therein, by those skilled in the art, without departing from the spirit 5 of the invention, or exceeding the scope of the appended claims.

I claim:—

1. The combination with a railway chair, the side walls of which are apertured and 10 the base of which is provided on either side of the center with an apertured seat, and railway rails, the confronting ends of which are slotted and adapted to lie within the chair, of a lug depending from each rail 15 and fitting within the apertured seats in the base of the chair, and a locking bar passing through the apertured side walls thereof and through the slotted ends of the rails to secure the chair and rails firmly together.
2. The combination with a railway chair, the side walls of which are apertured at 20 the center and one wall of which is apertured each side of the center, and railway rails adapted to lie in the chair, the confronting webs of which rails at each end 25 are slotted and near the slot provided with a recess, of a central locking bar passing through both apertured walls of the chair and the slotted ends of the rails, and side 30 locking bolts located in the apertures on each side of the center, the free ends of which fit into the recesses in the webs.
3. The combination with a railway chair having apertured side walls, and provided 35 near each end with integral blocks having depressed ways therein, and railway rails adapted to lie in the chair, the confronting ends of which are slotted, an integral boss having a seat on each rail so constructed as 40 to lie in place opposite the integral blocks of the chair, of a locking bar passing through the apertured walls of the chair

and the slotted ends of the rails, bolts in the depressed ways of the integral blocks of the chair, the free ends of which pass 45 into the bosses of the rails and lock the chair and rail securely together at the center and at each end.

4. The combination with a railway chair having apertured side walls, integral blocks 50 located near each end thereof, depressed ways therein, a base provided on each side of the center with an apertured seat, railway rails adapted to lie in the chair, the confronting ends of which are slotted, and 55 an integral boss on each rail so constructed as to lie when in place opposite the integral blocks of the chair, of a locking bar passing through the apertured walls of the chair and the slotted ends of the rails, bolts in the 60 depressed ways of the integral blocks on the chair, the free ends of which pass into the bosses on the rails, and a lug depending from each rail and fitting into the apertured seats in the base of the chair. 65

5. The combination with a railway chair, the side walls of which are apertured and the base of which is provided on either side of the center with an apertured seat, railway rails, the confronting ends of which are 70 slotted, adapted to lie within the chair, and a lug depending from each rail fitting within the apertured seats in the base of the chair, a locking bar passing through the apertured side walls and through the slotted 75 ends of the rails to secure the chair and rails together, of a supporting rib extending the length of one of the side walls and integral therewith, upon which the wheels of the car are carried without jolt over the juncture 80 of the rails.

In testimony whereof I affix my signature.

LUTHER SMITH.
